SWITCH JOINT PROTECTOR AND
RERAILER

Joseph Kostecka, Powhatan Point, Ohio

Application January 31, 1934, Serial No. 709,212

1 Claim. (Cl. 104—268)

This invention relates to a joint protector and rerailer for switches of railroad, the general object of the invention being to provide means for protecting the switch joints and for re-railing cars that have left the track at the switch and preventing the wheels of the car from spreading the switch when being pulled back onto the track.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a plan view of a track switch, showing the invention in use thereon.

Figure 2 is a top plan view with parts in section, showing one of the devices and the rails with which it is associated.

Figure 3 is a view of the spline plate.

Figure 4 is a section on line 4—4 of Figure 2.

Figure 5 is a section on line 5—5 of Figure 2.

Figure 6 is a section on line 6—6 of Figure 2.

Figure 7 is a section on line 7—7 of Figure 2.

Figure 8 is a section on line 8—8 of Figure 2.

As shown in Figure 1, a pair of the devices, shown at A and B, is used with each switch, one device being of left hand construction and the other of right hand construction, and each device is of elongated tapered form and includes the body 1 which extends between the rail 2, the transfer rail 3 and the switch point rail 4. A spline plate 5 is placed against portions of the rails 3 and 4 and on the opposite side from that which is engaged by the body 1 and two bolts 6 pass through the holes 7 of said plate 5, through holes in the rail 3 and through holes in a part of the body 1 and receive the nuts 8. A single bolt 9 passes through the hole 10 in the plate 5, through a part of the rail 4 and through another part of the body 1 and this bolt receives the nut 11, as shown in Figure 5. The two bolts 6 which pass through the transfer rail 3 are bolted tight with the spline bar, the rail and the body 1, but the bolt 9 should have sufficient play to permit opening and closing movement of the switch point.

One edge of the body 1 is thickened, as shown at 12, to fit in the space between the base and the head of the transfer rail and switch point 4 throughout the length of the body 1 and the other

edge of the body is shaped to engage a portion of the base and the lower part of the web of the rail 2, as shown in Figures 4, 5, 6 and 7. The upper surface of the body slopes downwardly from the thickened edge to the other edge, as also shown in these figures, but the upper part of the body, adjacent the thickened edge is formed with the recesses 13 and 14 to receive the inner ends of the bolts 6 and 9 and their nuts 8 and 11, as shown in Figures 5 and 7.

That end of the body remote from the switch point curves downwardly and outwardly, as shown at 15 in Figure 8, so that when a derailed car is being pulled from the frog 16 toward the switch point, the flange of the wheel will strike this end 15 and is thus raised while passing over the body to the proper height where the wheel will go back on the rail 2. Thus the wheels are caused to re-engage the track rails and they are prevented from spreading the switch. As will be seen from Figures 6 and 8, the body is built heavier at the joint of the rail 3 with the switch point 4 than elsewhere, in order to give additional strength at this point to protect the joint from being pushed outwardly.

From the foregoing it will be seen that I have provided simple means for protecting the joints of a switch and also means for re-railing cars that have left the track and in such a manner that they will not spread the switch when being pulled back on the track.

As is well known, when de-railed cars are pulled through switches, the switches are spread, thus causing the track to be damaged, but with my invention, the spreading of the switch is prevented as the two bodies will raise the wheels of the car so that they will engage the outside rails of the track and thus protect the switch from being spread and at the same time the device protects the joints from having play, thus making it practically impossible for cars to be de-railed.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

In combination with a main rail, a transfer rail and a switch point, a combined joint protector and re-railer comprising a tapered elongated body placed between the main rail and

adjacent parts of the transfer rail and switch point, said body having a thickened edge engaging the bases, webs and under portions of the heads of the transfer rail and switch point, the other edge of the body being comparatively thin and engaging a portion of the base and web of the main rail, the upper face of the body sloping downwardly and outwardly from the thick edge, an elongated splice plate contacting those sides of the transfer rail and switch points opposite

the sides engaged by the body, a plurality of bolts passing through the plate, the transfer rail and portion of the body, a single bolt passing through the plate, the switch point and a part of the body, said body having recesses therein to receive portions of the bolts and that end of the body remote from the switch curving downwardly and rearwardly.

JOSEPH KOSTECKA.
